UNITED STATES PATENT OFFICE

JAMES E. ECKERSLEY, OF ABERDEEN, WASHINGTON, ASSIGNOR OF ONE-HALF TO
ALEXANDER POLSON, OF HOQUIAM, WASHINGTON

SHINGLE AND VENEER CUTTING MACHINE

Application filed July 16, 1929. Serial No. 378,702.

One of the objects of my invention is to provide a machine for cutting shingles, battery separators and veneer which will practically eliminate waste such as sawdust in 5 that the machine is designed to handle blocks and reduces the spalts to a minimum.

Another object of my invention is to provide a plurality of block holding devices on one table with which a knife of special construction 10 cooperates.

Another object of my invention is to provide a machine of this character in which the knife contacts on the block with a shearing action, as distinguished from a splitting 15 action thereby enabling me to operate the machine with a minimum of power and without liability of dragging uncut fibers through the timber, thereby eliminating the possibility of breaking the grain and the other 20 fibers ahead of the knife which cause shattering of the stock.

A further object of my invention is to provide, in a machine of this character, means whereby the block may be evenly and 25 positively and intermittently moved toward the knife and held in proper position to be operated upon by the knife.

A further object of my invention is to provide feeding means whereby an irregular 30 block may be fed at one end more than at the other end to permit of the cutting of the butt end of a shingle from the same end of the block until the block becomes regular in shape, and thereafter to fit the block so that 35 the butt ends of the shingle will alternately be cut from one end of the block and from the other end of the block.

A further object of my invention is to provide means for feeding a plurality of 40 blocks whereby the blocks may be fed to cut standard shingles, or what is known, as "dimension" shingles or shakes.

A further object of my invention is to provide, in connection with the feeding rolls for 45 the block, means to hold a "spalt" while the shingles or other material are being cut therefrom, and with these and other objects in view my invention consists of the parts and combinations of parts as will be herein- 50 after more fully described.

In the drawings:

Figure 1 is a top plan view of a shingle and veneer cutting machine embodying my invention.

Figure 2 is a sectional view on the line 55 2-2, Figure 1, looking in the direction of the arrows.

Figure 3 is an enlarged detail top plan view of one of the block holding and feed sections of the machine. 60

Figure 4 is an enlarged detail sectional view on the line 4-4, Figure 3, looking in the direction of the arrow A.

Figure 5 is an enlarged detail sectional view on the line 4-4 looking in the direction 65 of the arrow B, Figure 3.

Figure 6 is an enlarged detail sectional view through the feeding roll mechanism.

Figure 7 is a top plan view of the machine with the operating parts removed from the 70 table, showing the eccentric mounting of the knife with reference to the table.

The base 8 of the machine may be of any desired construction and is provided with legs or standards 9 upon which is mounted a 75 table bed or platform 10 having block opening 10a. This base is also provided with a hub 11 in which one end of a shaft 12 is mounted in a fixed position. 13 is a pedestal in which the driving shaft 14 is journaled, 80 said shaft 14 having keyed thereto a worm gear 15 which meshes with a worm gear wheel 16 keyed to the shaft 12, there being a ball thrust bearing 17, interposed between the upper end of the hub 11 and the bottom face 85 of the worm gear wheel 16. A housing 18 is journaled on the shaft 12 and is provided with a tubular vertically disposed extension 19, in which extension the shaft 20 of the knife collar 21 is journaled. A spur gear 22 is keyed to the shaft 12 and is adapted to engage the spur gear 23 keyed to the shaft 20 of the knife collar 21. The knife collar is provided with a hub 24, the lower end of 90 which rests on a ball thrust bearing 25 supported on the upper end of the tubular extension 19. The shaft 20 is keyed to the knife collar by means of the key 26. From Figure 2 it will be seen that by reason of the position of the extension 19 from the housing 18 95 100

the knife collar 21 is placed eccentric to the shaft 12 and the center of the machine frame or table 10, and in its travel around the axis of the shaft 12 the knife collar maintains this eccentric position. The knife collar has a depression or seat 27 near its outer edge in which a circular knife 28 is seated, being secured thereon by the screws 29, as more clearly shown in Figure 2.

10 The casing or housing 18 is revolvably mounted on the shaft 12, and rigidly connected to the worm gear 16; the shaft 20 has a bearing 30 rigidly secured at its top in which a journal pin 31 is revolvably mounted, to which pin one end of a pitman 32 is connected. The other end of the pitman 32 is keyed to a shaft 33 mounted in a bearing 34 supported by the arms 35 on the table 10. This shaft 33 carries at its upper end a cam 35 which engages with the roller 36 mounted on the rocker arm 37—A, Figure 2, said rocker arm being keyed to the shaft 38. To the free end of the rocker arm 37, one end of a turn buckle rod 39 is connected, the other end of said rod 39 being pivotally connected to the arm 40 of the bell crank lever pivoted at 41. The arm 42 of the bell crank lever has pivoted to it a link 43, which in turn is pivotally connected to a weighted lever 44. This 20 weighted lever or arm 44 is connected to a cam case housing mounted on the shaft 45, which shaft carries a worm gear 46 that meshes with the worm wheel 47 that is keyed to the shaft 48 of the block feeding roller 49, the roller 49 turning in the direction of the arrow shown in Figure 6. When the high point of the cam 35 comes in contact with the roller 36 the rocker arm 37—A will be moved and pull the rod 39 in the direction of the arrow shown in Figure 4 whereby the bell 30 crank lever (40—42) is correspondingly moved and through the link 43 weighted lever 44 is moved whereby the shaft 45, worm gears 46 and 47, and shaft 48 are operated, which in turn revolves the block fitting rollers 49 in the direction of the arrows shown in Figure 6, thus feeding the block to the knife for the cutting operation.

50 Mounted in the casing is a pawl and ratchet mechanism 50 of the general type shown in my application, Serial No. 214,185, which pawl and ratchet mechanism is operated by the rod 39, bell crank arms 40 and 42, link 43, and weighted lever 44, so as to turn the shaft 45 only in one direction at predetermined timed intervals whereby the feed rollers 49 advance the block to be cut at predetermined timed intervals timed with the approach of the knife to that particular block which is to be operated upon, and this is repeated throughout the gangs of feed rollers in the machine.

60 The feed rollers and the mechanism for holding them up to their work, illustrated in Figure 6, are substantially the same as shown

in my Patent No. 1,552,985. The supports 51 for the rollers 49 are mounted on the table 10, as shown in Figure 6, and secured to these supports are pivotally mounted arms 52 having a forwardly projecting base 53, the forward pointed edge of which is adapted to engage the block of wood to be operated upon thereby maintaining the block in proper and predetermined position for operation, the arms being resiliently held in operative position by means of the springs 54. These supports 51 are in turn connected by means of a stub shaft 51a to a lever 56 (see Figure 3) which is provided with a pawl 57 adapted to engage the rack 58, so that in the event that it is necessary to move one of the supporting blocks 53, to accommodate a small block of wood to be operated upon, the lever 56 is moved in a proper direction and through the shaft 51a, the base 51 and roller 49 are slid 70 to their proper and desired position.

75 In order to hold the block operated upon against movement longitudinally relative to the roller 49 I provide a spring arm 59 pivotally mounted at 60, said arm having a screw threaded extension 61 on which is adjustably mounted a weight 62, whereby by adjusting the weight 62 on the arm 61 the desired tension on the spring 59 against the side of the block of wood can be maintained, thereby holding the block in proper position for operation.

80 On the table 10 is mounted a casting 63 (see Figure 5) in which is mounted a shaft 64 and the shaft 65. On the outer ends of the shafts 64 and 65 are mounted plates 66. On the shaft 65 I mount a collar 67, and between this collar and the wall of the casting 64 I provide a coil spring 68 (see Figure 3). The plate 66 to the right in Figure 3 is fixedly secured to the casting 63, while the plate 66 to the left in Figure 3 is adjustable, under the tension of the spring 68, toward and from the block of wood being operated upon, so that the distance between the plates 66 is automatically adjustable to accommodate the size of the wooden block to be operated upon between them thereby holding the block in proper predetermined position as it is being fed through the opening 69a in the table 10.

100 The block 69 to be operated (shown in Figure 3) not only rests against the casting 63, but it also rests against the plates or arms 66, and the spring 59 affords an additional support for the block whereby the block to be operated upon has, in effect, a four pointed support to hold it in proper predetermined position.

110 As it will be understood from the foregoing description, the cam 35 revolves with the knife so that as it reaches in succession the series of feed rollers and blocks mounted on the machine the high point of the cam operates the several parts as heretofore described to feed the block to be cut at the 115

proper point in the revolution of the knife, the pitman 32 controlling this movement. In this connection it is again noted that the knife is mounted eccentric to the axis of the shaft 12.

5 It is obvious that the machine may be used for wood slicing for various purposes including battery separators.

What I claim is:

10 1. In a machine of the character described, the combination with the bed plate, and its base, of a vertical fixed shaft in said base, a gear wheel keyed to said shaft, a support frame journalled on said shaft, a stub shaft revolvably mounted in said frame, intermeshing gears keyed to the said shaft and stub shaft, a knife revolvably mounted on said frame, block feeding devices on said bed plate, means connecting the said stub shaft 15 and feeding devices for operating said feeding devices in timed relation to the travel of the knife.

20 2. In a machine of the character described, the combination with a base and a bed plate support by said base on a vertical fixed shaft in said base, a frame journalled on said shaft, a stub shaft journalled in said frame eccentric to the vertical axis of the bed plate, means to revolve said frame around the vertical shaft, a plurality of block feeding devices mounted on said bed plates, a knife revolvably mounted on said frame, a pitman pivotally connected with said stub shaft, and means connecting the said pitman to said 25 30 35 block feeding devices to operate the block feeding devices in timed relation to the travel of the knife.

3. In a machine of the character described, the combination with a base and bed plate support thereby and provided with a plurality of block openings disposed concentrically with the vertical axis of the bed plate, block feeding devices operatively associated with said block openings, a revolving cam supported by said bed plate, means connected with the block feeding devices designed to be operated by said cam, and a knife mounted eccentrically to the vertical axis of the bed plate and adapted to revolve under said plate 40 45 50 and said openings, and means associated with said knife to operate said cam.

4. In a machine of the character described, the combination with a frame and bed plate supported thereby, a vertical fixed shaft in said frame, a gear wheel keyed to said shaft, a frame revolvably mounted on said shaft, a stub shaft revolvably mounted in said frame eccentrically to the vertical axis of the bed plate, a geared connection between the vertical shaft and stub shaft, a revoluble cam, means connecting said cam with said stub shaft, a plurality of block feeding devices mounted on said bed plate, and means connecting said block feeding devices adapted

to be engaged by said cam, and a knife revolvably carried by said stub shaft.

5. In a machine of the character described, the combination with a frame and bed plate supported thereby, of a vertical fixed shaft in said frame, a spur wheel also keyed to said shaft, a frame revolvably mounted on said shaft, a gear wheel suitably mounted on said frame, a stub shaft revolvably mounted in said frame eccentrically to the vertical axis of the bed plate, a spur wheel keyed to said stub shaft and adapted to intermesh with the spur wheel on the vertical shaft, a circular knife revolvably mounted on said frame, a plurality of block feeding devices on said bed plate, a pitman, one end of which is pivotally secured to the stub shaft, a cam connected to and operated by said pitman, operating means for the block feeding devices adapted to be operated by said cam, whereby the block feeding devices are operated successively in timed relation relative to the travel of the said knife.

6. In a machine of the character described, the combination with a bed plate having a plurality of block openings therethrough, block feeding devices operatively associated with said openings, a rotatable knife, a mounting for said knife rotatable about an axis eccentric to the bed plate, and means operated from the eccentric rotatable mounting to operate said feeding devices.

In testimony whereof I affix my signature.

JAMES E. ECKERSLEY.
